Des. 199,991
Patented Jan. 5, 1965

199,991

SERVING TRAY

Charles R. McManamey, 2500 Gary Ave., Lansing, Mich.

Filed June 18, 1964, Ser. No. 38,468

Term of patent 14 years

(Cl. D44—10)

FIG. 1

FIG. 2

FIG. 3

FIG. 4

FIG. 5

FIGURE 1 is a top view of a serving tray, showing my new design;

FIGURE 2 is a front elevational view;

FIGURE 3 is a cross-sectional view thereof, taken on line III-III in FIGURE 1;

FIGURE 4 is a cross-sectional view thereof, taken on line IV-IV in FIGURE 1; and

FIGURE 5 is a cross-sectional view thereof, taken on line V-V in FIGURE 1.

I claim:

The ornamental design for a serving tray, as shown.
